UNITED STATES PATENT OFFICE.

OSCAR KRINER, OF MARTINSVILLE, INDIANA.

OIL-CAN.

1,263,682.

Specification of Letters Patent. Patented Apr. 23, 1918.

Application filed September 26, 1916. Serial No. 122,274.

To all whom it may concern:

Be it known that I, OSCAR KRINER, a citizen of the United States, residing at Martinsville, in the county of Morgan and State of Indiana, have invented certain new and useful Improvements in Oil-Cans, of which the following is a specification.

This invention has relation to oil containers or the like, and has for its object to provide a container particularly adapted for kerosene, gasoline, etc., and embodying means for preventing splashing out of the contents through the filling opening of the container when the same is inverted for the purpose of discharging its contents through the spout into another receptacle.

Another object of the invention is to provide a container having the above named characteristics wherein the anti-splashing means as above set forth also constitutes a closure in one position for the container thereby obviating the necessity for an additional closure.

In addition to the foregoing, my invention comprehends improvements in the details of construction, and arrangement of parts to be hereinafter more fully described and particularly set forth in the appended claims.

In the accompanying drawings, in which similar and corresponding parts are designated by the same characters of reference throughout the several views in which they appear:

Figure 1, is a view in vertical section of an oil container constructed after the manner of my invention.

Fig. 2, is a view thereof in end elevation,

Fig. 3, is a view of the container in plan, and

Fig. 4, is a view in vertical section of a modified form of oil container.

With reference to the drawings, 1 indicates the conventional type of oil container having an integrally formed top, 2, which in the present instance is pressed upward to form a hemispherical hollow container top 3. The hemispherical container top is formed adjacent one side portion thereof with a filling opening 4, surrounded with a vertically extending flange 5, while the container top 3 at an opposite point of the filling opening is formed with a discharge pipe 6.

A movable baffle member 7 is provided

interiorly of the container, said baffle member 7 being in the form of a hemispherical shell, having its outer surface curved to conform to the inner curvature of the hemispherical container top 3 as illustrated in Fig. 1 of the accompanying drawings. The baffle member 7 is provided at its zenith with a vertical stem 8 extending from the exterior of said member in a substantially radial direction through an opening provided therefor in the hemispherical container top 3. A cam lever 9 is provided in the nature of a single strand of wire bent upon itself to form a handle portion 11, the strands adjacent their ends being bent at substantially right angles to the handle portion as indicated at 11, the extremities of the strands being further bent to form loops 12 which encircle a horizontal portion 13 formed at the upper end of the stem 8. A cam lever guide 14 is provided in the nature of a bridge piece adapted to extend transversely above the handle portion 10 of the cam lever adjacent its bent portion 11, said bridge piece being secured at its end to the exterior surface of the container top 3 as indicated at 15.

It will be obvious, upon reference to Fig. 1, that with the cam lever disposed as indicated therein in full lines with the handle portion adjacent the container top 3, the curved portion 11 of said cam lever will be compelled to bear against the top of the container top 3 owing to the provision of the guide 14 thereby disposing the terminal 12 of said lever in an upright position and as a consequence drawing the stem 8 upward and the hemispherical baffle member 7 in close engagement with the interior surface of the hemispherical top 3. In this manner a closure for both the filling opening 4 and the spout 6 is provided.

When it is desired to discharge the contents of the container, the cam lever is rocked toward a position indicated in dotted lines in Fig. 1 thereby disposing the looped terminal 12 thereof in engagement with the container top 3, thereby depressing the stem 8, and consequently the hemispherical baffle member 7 toward a position indicated in dotted lines in said figure. In this manner, when the container is inverted to discharge its contents through the spout 6, the splashing of the contents through the filling open-

ing 4 is absolutely prevented by reason of the baffle member 7 which provides a constricted annular passage between the exterior surface and the inner edge of the 5 container top 3 through which the oil or the like must pass before reaching the spout 6. Thus the member 7, not only serves as a baffle plate to prevent splashing of the oil from the container, but also to provide a close- 10 sure for both the spout and the filling opening when the container is to be transported.

In Fig. 4, of the drawings I have illustrated a modified form of my invention wherein the same principle set forth above 15 is embodied, however in a container of a different type. In this form of container, the body portion 16 is formed with a conical cover 17 having its apex extended vertically and threaded as at 18 to receive a correspond- 20 ingly threaded top 19. A spout 20 is provided and is formed upon the cover 17 adjacent its lower periphery.

A conical baffle member 21 is disposed interiorly of the container, said baffle member having its sides constructed upon an angle to correspond to the configuration of the container cover 17, the baffle member being disposed therein so as to space its exterior sides from the interior surface of the cover member 17, the annular edge 22 of the baffle member being closely spaced from the top edge of the main container portion 16 so as to provide a constricted annular passage 22. Lugs 23 formed integrally with the edge of 35 the baffle member 21 may be provided to afford a means whereby said baffle member is secured to the interior of the container.

The threaded extension 18 of the container top and the top 19 which is applied thereto 40 are both provided with openings 24 and 25 which may be brought into registration when the cap is rotated for that purpose.

In the operation of this form of my invention, when it is desired to discharge the 45 contents of the can, the cap 19, is rotated as before described to bring its opening and the opening 24 in registration thereby establishing a vent to permit entrance of air to displace contents of the can issuing from 50 the spout when the can is inverted. The splashing of the contents during the discharging operation is however, prevented because of the baffle member 21 in a manner similar to the baffle member 7 of the form 55 first described. In the present instance, the contents of the container must effect an exit through the annular space 22 before reaching the spout 20 thereby reducing any wave-like motion which the contents of the can 60 may have and permitting its flow from the spout to be in a smooth stream. This effect of an even flow of oil from the spout, is similarly carried out in the form of my invention first described through the medium 65 of the hemispherical baffle member 7. In

the present instance, when all or part of the contents of the container has been delivered, the cap 19 may be rotated so as to lap the opening 24 thereby preventing loss of fluid through said opening.

While I have illustrated and described my invention with some degree of particularity, I realize that in practice various alterations thereover may be made, and I therefore reserve the right and privilege of changing the form of the details of construction, or otherwise altering the arrangement of the correlated parts without departing from the spirit of the invention, or the scope of the appended claims.

Having thus described my invention, what I claim as new and desire to secure by Letters Patent is:

1. An oil container having a substantially hemispherical cover plate, a spout leading 85 from said cover plate, and a hemispherical baffle member within the container for fitting engagement with the cover plate and movable into contact with the inner surface of the cover plate, to form a closure for the 90 spout, and movable in spaced relation to said cover plate to form a baffle to retard the velocity of the flow of oil to said spout.

2. An oil container having a hemispherical top plate, said top plate having a filling 95 opening and a discharge spout, and a hemispherical baffle member within the container for movement into fitting contact with the inner surface of the top to form a closure to the filling opening and spout, said 100 baffle member being movable to space the sides of the same from the top plate to retard the velocity of the flow of oil toward the spout when the can is inverted, and to prevent splashing of the contents through 105 the filling opening.

3. An oil container having a hemispherical top, said top having a filling opening and a discharge spout, a hemispherical baffle member within the container, and means 110 for moving said baffle member into fitting contact with the interior surface of the top to form a closure for the filling opening and spout, said means being utilizable to move said baffle member away from the inner surface of the top to define a constricted annular space between the rim of said baffle member and the rim of the hemispherical top to retard the velocity of the flow of oil toward 115 said spout when the can is inverted, and to prevent splashing of its contents through 120 the filling opening.

4. In an oil container, a hemispherical cover-plate, having a discharge spout at one side, a filling opening at the opposite side, and a central opening, a hemispherical baffle member within the can, a stem mounted on said baffle member to extend through the central opening of the hemispherical top, a T-shaped head on the projecting end 125 130

of said stem, a cam member formed of a pair of parallel strands of wire bent at one end at right angles, and having eyes formed at the terminals of said bent ends to receive the terminals of the T-shaped head, and a bail secured to the hemispherical top to receive the handle end of the cam shaped member whereby the baffle member may be moved to a position in contact with the hemi-

ispherical member or depressed in spaced 10 relation thereto.

In testimony whereof I affix my signature in presence of two witnesses.

OSCAR KRINER.
